CAN OPENERS

Albert Henry Franks Perl, Norton, Stourbridge, England, assignor to Joseph Billingham Limited, Cradley Heath, Staffordshire, England, a company of Great Britain

Filed Apr. 10, 1961, Ser. No. 101,763

Claims priority, application Great Britain Apr. 13, 1960
4 Claims. (Cl. 30—23)

This invention relates to a can opener of the scissors type which is provided with a piercing blade to pierce the can initially and allow a cutting blade of the scissors to be inserted and which has adjacent and at right angles to the piercing blade a hook or hooks. The can opener is applied to the can in such a way that the edge of the can is engaged by the hook or hooks and the piercing blade is below the level of the hooks and opposite the side of the tin. To pierce the can the opener is rotated about the line of engagement of the hooks and can to force the piercing blade through the wall of the can. Such a can opener is hereinafter referred to as of the kind described.

The present invention consists in a can opener of the kind described wherein the piercing and cutting blades are both flat and each is separate from the other and made without bending by cutting in the form of a blank from sheet or strip metal, the piercing and cutting blades being mounted on the structural members of the can opener.

This invention enables each of the separate components of the can opener to be made from the most suitable materials, for example hardened high carbon steel for the cutting parts and the hook or hooks and a more ductile steel suitable for press-work for the structural members. Bending and other deformation operations which are difficult and unsatisfactory on hard materials are avoided in the manufacture of the cutting components. The use of these more costly materials can be confined to components for which they are really necessary and the cutting components can be of relatively simple shape so avoiding complications in sharpening.

An embodiment of the invention will now be described by way of example with reference to the accompanying drawings in which,

FIGURE 1 is a cross-section of a can opener according to the present invention.

FIGURE 2 is a plan view of a piercing blade.

FIGURE 3 is a perspective view of the can opener in the initial position for piercing the wall of the can.

FIGURE 4 is a fragmentary view of the can opener in the process of piercing the wall of the can.

FIGURE 5 is a perspective view of the can opener cutting the wall of the can.

The can opener, as shown in the drawings, is of the scissors type and has a pair of channel section handles 5 and 6 which are pivotally connected adjacent one end with the open faces of the channel opposing each other. The handles 5 and 6 are formed by a pressing operation from a ductile sheet or like metal producing the channel section and curving the handles along their length as shown in FIGURE 1, the width of the channel and the curve of the handles affording a comfortable hand grip for the user whilst operating the can opener. The first handle member 5 has the base of the channel removed

2

along part of its length producing a bifurcated portion 7 with the two limbs having parallel outwardly presented substantially right angled edges 8 which curve inwards towards the end of the handle to meet the inner edges of the limbs. The bifurcated portion 7 is shaped by the pressing operation in such a way that the distance between the outwardly presented edges 8 and the ends of the limbs is substantially less than the distance between the inner edges of the limbs and the normal width of the channel section of the remainder of the handle. The second handle member 6 is pivotally connected to the bifurcated end 7 of the first handle member 5 by a rivet 9, which passes through holes provided through the walls of the second handle member and lugs 10 formed on the inner edges of the first handle member, which extend between the walls of the second handle member and a spacing member 11 provided between the lugs 10 and the ends of the limbs of the bifurcated portion 7 of the first member.

20 A cutting blade 12 is pivotally connected at an intermediate point to an intermediate point in the first handle member 5 to oscillate about an axis 13 and so that it lies between the limbs of the bifurcated portion. This cutting blade 12 is flat throughout and is made in the form of a blank from high carbon steel sheet, that is to say steel having a carbon content of between 0.6% and 1.2%, and has an inwardly extending arm 14 and an outwardly extending arm 15 with an inwardly presented cutting edge 16. The cutting edge 16 is knife edged that 30 is, it is of acute-angle cross-section bounded by oppositely inclined chamfered flanks and is substantially straight for the greater part of its length but near the end of arm 15 it curves outwardly towards the outer edge of the arm and meeting that edge to form a point 17 at the end of the arm. A link 18 is pivoted at one end 19 to the free end of the inwardly extending arm 14 and pivoted at the other end 20 to the second handle member 6 near its pivotal connection to the first handle member, thus forming a compound linkage between the handles and 35 the cutting blade 12. The link 18 is of channel section having its open side facing the pivotally connected ends of the handles. The outside dimension of the section is slightly less than the inside dimension of the handles along the greater part of its length. The limbs of the 40 portion of the link adjacent its end 19 are pressed inwardly close to the end of the inwardly extending arm 14 of the blade, which is pivotally connected to the link between the limbs by a pivot 22, to prevent axial movement of the arm between the limbs of the link and the end portion of the base is cut away to provide a recess 21. At the other end 20 of the link the base of the channel is cut centrally for a length approximately equal to the depth of the channel section and the two halves of the base so formed are turned back to form extensions of 45 the limbs and leaving a recess 23 in the base of the link the end of which is between the two pivoted axes of the link.

The handles are urged apart by spring means provided by a square section bar spring 24 which is anchored at 50 one end 25 to the free end of the second handle member. The anchorage is provided by the engagement of the end 25 of the spring, which is curved outwardly to form a shallow hook shaped portion as shown in FIGURE 1, with an inwardly directed loop 44 formed in

the member between a pair of openings 45 cut in the base of the channel of the member. At the other end the spring bears against the end of the recess 23 formed in the link 18 and extends sufficiently between the limbs to prevent its becoming disengaged. The spring 24 tends to urge the handle members apart by virtue of its being bent concavely round the curved portion 26 of the second handle member between its anchored end and the end which engages the link. A stop limits the extent of the separating movement of the handle members. This is provided by a projection 27 which is formed at the end of the inwardly extending arm of the blade and which engages the end of the recess 21 at the end 19 of the link when the handle members reach their required separation limit and further outward movement of the members is prevented. By means of the compound linkage, movement of the handle members towards one another causes the cutting edge of the blade to enter into the gap between the edges 8 of the limbs of the bifurcated portion 7 in a scissor action cutting the material which is extended across the gap. Because the handle members are spring urged apart the cutting edge is normally outside the gap. However a catch 28 pivotally mounted at an intermediate point in a cut-away portion 29 of the face of the first handle member can be moved so that a sear 30 formed in the catch engages an open-ended slot 31, provided in the inwardly extending arm of the blade, when the handle members are brought towards each other. The slot 31 is radial to the pivotal axis 13, and holds the can opener in the closed position against the action of the spring 24.

A flat piercing blade 32 of substantially pentagonal shape, as shown in FIGURE 2, is made from high carbon steel sheet and is formed with a pair of cutting edges 33 meeting in a point, each edge making the same angle with the major axis of the piercing blade so that in plan view the piercing blade resembles a rectangle with an obtuse angled isosceles triangle constructed on one side as base. In both sides of the rectangular portion of the piercing blade adjacent to the side on which the triangle is constructed recesses 34 are formed. A pair of hook members 35 are also flat and blanked from high carbon sheet steel, each having a pair of notches 36, complementary in width to the sheet thickness of the piercing blade, directly opposite each other cut into opposite side edges of the member, leaving a width of metal between the ends of the recesses 36 sufficient for the member to be received into the recess 34 provided in the piercing blade. The arrangement is such that the piercing blade and the hook members are separably joined together by a double H-type joint which prevents movement of the hook members separately from the piercing blade in the planes normal to the blade and parallel to its main axis. The hook members 35 are assembled parallel to each other and normal to the surface of the piercing blade and close to its apex, so that the hooks overlie one face of the blade, and are directed towards the apex as shown in the drawings. The hook and piercing blade assembly is mounted on the bifurcated end of the first handle member so that the apex of the blade and the hooks are directed forwards that is, away from the axis of the handle, the surface of the piercing blade opposite to that which the hooks overlie bearing against the inwardly presented edges of the handle member between the lugs 10 and the end of the limbs and against the spacing member 11, the edges and the spacing member providing a flat surface supporting the piercing blade. The tails of the hook members 37 on that side of the piercing blade which bears against the inwardly presented edges and the spacing member straddle the end of the handle member and the assembly is secured by a rivet 38 which passes through this portion of the hook members, the limbs of the handle and the spacing member 11. To prevent possible rotation of the assembly about the rivet 38 when the piercing blade is in use, the end of the pierc-

ing blade opposite the pointed end engages slots 39, FIGURE 1, provided in the lugs 10 adjacent the inwardly presented edges of the first handle member.

The hook and piercing blade assembly described is a preferred form but in an alternative assembly a single central hook member could be mounted in a plane parallel to that of the two said hook members and passing through the apex of the blade.

To open a can, the opener, preferably with the handle members closed together, is first applied to the can, as shown in FIGURE 3, in such a way that the rim of the can, as indicated by reference 40 in the drawing, is engaged by the hooks and the piercing blade is below the level of the hooks and opposite the side 41 of the can. To pierce the can the opener is swung down about the line of engagement of the hooks and rim 40 in the direction indicated by the arrow to force the piercing blade through the wall 41 of the can, as shown in FIGURE 4, producing a triangular shaped opening 42 through the wall 41 just below the rim. The pierced opening 42 is sufficiently wide to enable the cutting blade to pass easily into position for cutting, when the handles are released from the closed position. Cutting is done with a scissor action round the wall of the can, as shown in FIGURE 5, in a clockwise or counter clockwise direction whichever the user finds more convenient. The gap between the outwardly presented edges 8 of the bifurcated end of the first handle and the cutting blade is such that the material extending across the gap is bent into the gap between the limbs before actually being cut. This action produces an outwardly directed lip 43, as shown in FIGURE 5, round the wall of the can and on each side of the cut. To prevent the can slipping from between the cutting blade and the outwardly presented edges 8 during the cutting operation the edges 8 may be serrated.

What I claim is:

1. A can opener comprising in combination a first handle member having a portion bifurcated at one end to form two limbs having parallel outwardly presented, concavely curved edges, a second handle member pivoted at one end to the bifurcated end of said first handle member, a flat cutting blade lying between the limbs of said bifurcated portion and pivoted at an intermediate point to an intermediate point on said first handle member and having an inwardly extending arm provided in its edge adjacent said first handle member with an open-ended slot radial to said pivot of the blade and first handle member, and an outwardly extending arm with a substantially straight inwardly presented, knife-edged cutting edge, a link pivoted at one end to the free end of said inwardly extending arm and pivoted at its other end to said second handle member, spring means urging the handle members apart and a catch pivotally mounted on said first handle member and having a sear engageable in the closed position of the handle members with said open-ended slot.

2. A can opener comprising in combination a first handle member having a portion bifurcated at one end to form two limbs having parallel outwardly presented edges, a second handle member pivoted at one end to said bifurcated end, a cutting blade lying between the limbs of said bifurcated portion and pivoted at an intermediate point to an intermediate point in said first handle member and having an inwardly extending arm and an outwardly extending arm with an inwardly presented cutting edge, a link pivoted at one end to said free end of the inwardly extending arm and pivoted at the other end to said second handle member near its pivoted connection to said first handle member, spring means urging said handle members apart and a stop limiting the extent of such separating movement, movement of said handle members towards one another causing the entry of said cutting edge into the gap between the edges of said limbs in scissor action.

3. A can opener comprising in combination: a first

handle member; a cutting blade pivoted at an intermediate point to an intermediate point on said first handle member and having a sharpened cutting edge cooperating in scissor-like action with at least one edge of said first handle member; a second handle member pivoted on said first handle member; and linkage means interconnecting said cutting blade and said first and second handle members for actuating said cutting blade with mechanical advantage.

4. A can opener according to claim 3 and further comprising: spring means connected between one of said handles and said linkage means for urging said handle members apart; and catch means positioned between one of

5
6
said handles and said linkage means for releasably retaining said handle members together against the action of said spring means.
